UNITED STATES PATENT OFFICE

2,671,281

VEHICULAR APPARATUS FOR REMOVING
SNOW AND ICE FROM STREETS AND
THE LIKE

George Salmen, Los Angeles, Calif.

Application May 1, 1951, Serial No. 224,011

1 Claim. (Cl. 37—45)

1

My invention relates to vehicular apparatus primarily intended for removing snow and ice from areas such as surfaced roads, streets and highways, although the apparatus may also be used for other purposes having similar requirements.

It is common knowledge that the usual type of snow removing apparatus, such as snow plows, are not very satisfactory in use since although they are effective in scraping the surface snow to the sides of a road, the heaped snow has to be removed by other machines, or by men who shovel the snow into trucks.

In addition, if ice has formed, as often happens, because of the snow melting under a warm sun during the day and then freezing during the night, such machines do not operate to advantage since the plow blades tend to slide over the frozen surface.

It is an object of my invention to provide snow and ice removing apparatus which incorporates means having a combined cutting and shoveling action, which not only removes surface or loose snow, but also digs into and breaks up compacted snow or ice, or a covering of both, in a positive and rapid operation.

Another object of my invention is to provide vehicular apparatus for breaking up and gathering snow and ice on surfaced areas which is, in addition, provided with conveyor means whereby the material removed from the surface of the road or other area, is raised to a level from which it may be dumped into trucks travelling alongside the apparatus and removed in a continuous operation not requiring the use of a gang of loaders.

A further object of my invention is to provide an automotive vehicular apparatus for breaking up and removing ice and snow from surfaced areas and dumping the removed material, which is simply and strongly constructed and arranged so that the parts subject to the most wear and shock may be readily replaced when required.

One difficulty in ensuring satisfactory removal of snow and ice from roads is that high spots, rocks or other obstructions in the road may cause unevenness at some points and a scraping blade might be either stopped or damaged by contact with the obstructions or the whole blade might be raised in passing over the obstruction.

Accordingly it is another object of my invention to provide an apparatus provided with a plurality of means having a digging and shoveling action and which are resiliently mounted so that they will act efficiently on such rough surfaces without being damaged thereby.

2

Still further objects and features of my invention will appear in the following description with reference to the accompanying drawings of an embodiment of my invention at present considered preferable by me.

In the drawings:

Fig. 1 is a side elevation view of the vehicular snow and ice removing apparatus of my invention, with that chain for driving the front vehicle wheels nearest the viewer, being broken away to reveal parts not otherwise disclosed.

Fig. 2 is a front view elevation of the apparatus, the body of a truck in position for receiving removed material dumped from the apparatus, being shown in section.

Fig. 3 is a plan view of the apparatus shown in Fig. 1.

Fig. 4 is a cross section on line 4—4 of Fig. 1.

Fig. 5 is a fragmentary cross section on the line 5—5 of Fig. 1, but on a larger scale.

Fig. 6 is a fragmentary cross section on the line 6—6 of Fig. 2, but drawn on a larger scale.

Fig. 7 is a fragmentary cross section on the line 7—7 of Fig. 3, but on a larger scale.

Fig. 8 is an enlarged view showing in perspective one of a plurality of plates incorporated in a digging and shoveling means of the apparatus.

Fig. 9 is an enlarged detail perspective view of one of the members in which the plates shown in Fig. 8 are mounted.

In Fig. 1, the numeral 10 indicates generally the bed frame of a vehicle on which the snow and ice removing means of my invention are mounted, and which comprises longitudinal members 11 and transverse members 12. The vehicle is provided with front wheels 13 and 14 mounted on an axle 15 carried in bearing brackets 16, 17, bolted or otherwise connected to the frame members of the vehicle. A pair of steerable rear wheels 18, 19 are mounted in castoring forks 20, 21 rotatably mounted at the back of the vehicle in bearings 22, 23 secured to the vehicle frame.

Arms 24, 25 are secured to the forks 20, 21 and are connected by a bar 26 pivotally secured to the arms. A steering column 27 is fitted at its upper end with a steering arm 28, and at its lower end with an arm 29. The outer end of arm 29 is fitted with a depending pin 30 rotatable in the bar 26, thus affording a direct steering arrangement for the rear wheels 18, 19. It is obvious that any other suitable steering arrangement may be provided, that described being given by way of example only.

An engine or motor, generally indicated at 31,

is mounted at the rear of the frame 10. The engine and all controls for the apparatus are arranged within easy reach of the driver's seat 33, and a closed driver's cab 34 is provided with the door thereof indicated at 35.

A main engine driven shaft 36 is arranged transversely at the rear of the frame 10, and a clutch 37 operated by a lever 38 is provided to connect and disconnect the shaft 36 to the transmission contained in a box 37a. Rear sprocket wheels 39, 40 fixed on the ends of the shaft 36, sprockets 41, 42 fixed on the shaft 15 and drive chains 43, 44 connecting the sprocket wheels provide a driving mechanism for wheels 13, 14.

A frame comprising vertical beams 45, 46 are mounted toward the front of the main frame 10, and are braced from the longitudinal members 11 by diagonal struts 47, 48.

A frame, generally indicated at 51, is pivoted at its upper end on a transverse shaft 52 carried in bearings 53, 54 secured to the vertical beams 45, 46 adjacent the upper ends thereof. The frame comprises spaced side members 55, 56, in the lower ends of which is mounted a shaft 57. Upper sprockets 58, Fig. 6, are fixed on the ends of shaft 52, and lower sprockets 59, Fig. 7, are similarly fixed on the ends of the lower shaft 57 on the inner sides of the side members 55, 56. Endless chains 60, 61 are trained around such upper and lower sprockets.

A wide and endless conveyor belt 62 of suitably flexible and strong material, such as heavy webbing is secured along its edges in any suitable manner to chains 60, 61. Angle bars 63 are riveted to extend across the width of the conveyor belt and are spaced along the length thereof and prevent ice and snow from sliding downwards on the upper stretch of the belt.

The lower end of the conveyor frame 51 is supported for vertical movement by an arm 64 of a bell crank lever pivoted at 65 in a bearing supported on the floor 12a of the cab. The other arm 66a of the bell crank lever is fitted with a handle 67 and a releasable detent 68 engageable with a notch 66 in a quadrant 69. Arm 64 is pivoted at its outer end to a link 70 which in turn is pivoted on a cross rod 71 midway of its length. Rod 71 is mounted at its ends in triangular brackets 72, 73 extending upwardly from the lower ends of the frame side members 55, 56.

Side plates 74, 75 extending upwardly and over the edges of the belt 62 are supported by brackets 76, 77 and 78, 79 bolted or riveted to the side members 55, 56 and to the plates. These plates serve to confine the snow and ice on the belt 62.

Snow and ice loosening and shovelling means generally indicated at 80, and a gathering and guiding means generally indicated at 81, are carried by the frame 51.

The snow and ice loosening and shovelling means 80 is mounted on a shaft 82 carried at each end in bearing blocks 83, 84 vertically movable in supporting brackets 85, 86, depending from the side members 55, 56 and formed with vertical guideways 87, 88 (Fig. 4) for the bearing blocks. Coil springs 89, 90 are positioned between the tops of guideways 87, 88 and the tops of the bearing blocks.

The means 80 comprises a plurality of units 91 (Fig. 9) all fixed to the shaft 82. Each unit 91 comprises a hub 92 receiving the shaft 82, a longitudinal keyway 93 being provided alignable with a longitudinal keyway 94 in the shaft and both receiving a key 94a to fix the hub to the shaft. Arms 95 are fixed to and radiate from the

hub 92 and are tapered from the hub outwardly to their free ends into relatively sharp transverse edges 95a. The side faces of the arms 95 are provided with parallel flanges 96, 97, the grooves 98 between the flanges being aligned with grooves 98a in the hubs 92. Plates 100 (Figs. 4 and 8) are fitted into the facing grooves of the arms of adjacent units 91, and are secured therein by screws 101. Six units 91 are shown in Fig. 4 and 10 five plates 100 are secured between each series of aligned arms 95 to span the space between the same.

Sprocket wheels 105, 106 are secured on the ends of shaft 82, and other wheels 107, 108 are mounted on the ends of shaft 57 on the outer sides of the side members 55 and 56. Endless chains 109, 110 are mounted on sprockets 105, 107, and 106, 108 respectively. These wheels and chains provide means for driving the units 91 20 from the shaft 57, as will be understood.

The gathering and guiding means 81 comprises a blade 111, Figs. 1 and 7, inclined rearwardly and upwardly and curving around the lower end of the conveyor belt 62. The leading edge of the blade 25 111 is preferably made of especially tough steel and fitted as a renewable element 112 secured to the lower edge of the blade. The blade 111 is held in place on the frame of the vehicle by depending side plates 113 secured at their upper 30 ends to brackets 72, 73. The blade is secured at its upper edge to a rod 71 by brackets 114, and is supported intermediate its length by a rod 115 which is secured at its ends in the side plates 113. To ensure that the lower edge of the blade 35 35 being held closely adjacent the surface being cleared but to prevent the edge digging into such surface, rollers 117 are mounted on a rod 118 supported at its ends in the side plates.

The conveyor belt 62 delivers material to a 40 transversely arranged delivery conveyor, generally indicated at 119, supported by the posts 45, 46, and a second pair of posts 120, 121 supported at their lower ends on the side members of the vehicle frame and braced by diagonal braces 122, 123 secured to cross member 12. Posts 120, 121 45 may be secured at their upper ends to the upper ends of posts 45, 46 by any suitable means as, for instance, by the plate 124.

Sprockets 125, 126 (Fig. 5) are mounted adjacent posts 45, 120 and posts 46, 121, on shafts 50 127, 127a mounted in bearings in transverse lengths of angle irons 129, 130 extending between posts 45, 46 and posts 120, 121. Endless chains 131, 132 are mounted on the sprockets 125, 126, 55 and an endless conveyor belt 133 of suitable pliable material such as heavy webbing is secured to the chains. To the chains and the conveyor belt 133 transverse angle bars 134 are secured in any suitable manner.

A sprocket 135 is secured on shaft 127a and a sprocket 136, aligned with sprocket 135, is mounted on a short shaft 137 mounted in brackets 138, 139 (Fig. 3) secured on the upper ends of posts 46, and 121. A sleeve 140 is mounted on shaft 137 for axial adjustment, while held for rotation with the shaft by a spline or key connection therewith, as indicated at 141. The sleeve 140 may be moved axially by a pin 142 projecting from a horizontal lever 143 and engaging between collars 144, 145 fixed on the sleeve. Lever 143 is mounted on a pivot 146 projecting from a crossbar 147 secured to the posts 46 and 121, crossbar 147 also serving to support, or being formed to provide the brackets 138, 139.

A pair of opposed bevel gears 148, 149 are fixed

on sleeve 140 and are spaced apart so that either one or the other may be brought into mesh with a bevel gear 150 fixed to the upper shaft 52.

The shaft 52 is rotated when required from the shaft 36 through a sprocket 151 secured on shaft 52, driving chain 152 and sprocket 153 fixed on a sleeve 154, freely rotatable on shaft 36.

Sleeve 154 may be connected to shaft 36 by a clutch 155 comprising teeth formed on a side face of sleeve 154 and on a side face of sleeve 156 slideable on, but held for rotation with shaft 36 by a spline connection indicated at 157. The clutch sleeve 156 may be moved on shaft 36 toward sprocket 153 to clutch the wheel 153 to the shaft 36, or in the reverse direction to leave the sprocket disconnected from the shaft, by means of a lever 159 pivoted on a bracket 160 projecting from and secured to the side frame of the vehicle.

One end of the lever 159 is provided with a pin 161 projecting into the groove 162 of the sleeve 156. The opposite end of lever is connected by a push-pull rod 164 to an arm 165 projecting from a vertical shaft 165a supported in a vertical tubular bearing 166. An operating lever 167 is secured to the upper end of shaft 165a. The clutch may be held in engaged or disengaged position by any suitable means associated with the shaft 165a.

The material deposited on delivery conveyor belt 133 may be delivered from either side of the machine, depending on the setting of the bevel gear train 148, 150, 149, by a detachable delivery chute 169 removably secured by bolts 170, to the vertical posts at the front of the machine. As shown in Fig. 2 the delivery chute is arranged for dumping material into a truck body 171 at the side of the vehicle. In the operation of the apparatus, the engine 31 operates to drive the wheels 13 through the chains 43, 44, and thus propel the vehicle forwardly as indicated by the arrow in Fig. 1. During travel of the vehicle to a road, street or highway to be cleared of snow and ice, the arm 66 is in a position to the left end of the quadrant 69 in which it is held by the detent 68. In this position of the arm 66 the frame 51 is held in the elevated position indicated in broken lines in Fig. 1, so that the blade 111, the rollers 117, and the arms 95 are all elevated to positions which will clear road surfaces over which the vehicle may travel to the particular road to be cleared.

Upon reaching the road to be cleared the operator moves the arm 66 to its forward position thus lowering the blade, rollers, and arms 95 to operative positions, as shown in Fig. 1. By now actuating the arm 165 the clutch 155 may be operated to connect the shaft 36 to the sprocket 153 through chain 152 and sprocket 151 to drive shaft 52 for driving the conveyor belt 62 in the direction of the arrow in Fig. 1. With driving of the conveyor belt the shaft 57 is also driven through the chains 60, 61 to drive the shaft 82 so that the arms 95 with the plates 100 are rotated in the direction of the arrow in Fig. 1.

Thus the arms 95 below the shaft 82 are driven downwardly, rearwardly and then upwardly to cause their outer relatively sharp ends 95a to dig and cut the snow and ice along lines extending lengthwise of the highway. The outer edges of the plates may also be made relatively sharp so as to dig and cut the snow and ice on lines extending across the highway. Thus the arms and plates coact to break up and thus loosen the snow and ice as the vehicle moves along a highway.

Because of the width of the plates 100 and the

fact that they span the arms of adjacent units, these plates act as shovels to sweep the loosened ice and snow rearwardly and upwardly against the blade 111, which is carried forwardly with the

5 vehicle, the material being guided upwardly over and onto the surface of the conveyor 62. The angle bars will ensure upward movement of the material between the sides 74-75 of the conveyor and the delivery of the material onto the transverse conveyor belt 133.

It may be desired to deliver the material cleared from the street to either one side or the other of the vehicle into a truck travelling alongside the vehicle. This is provided for by the driving gear arrangement for the conveyor belt 133 and the detachable delivery chute 164. If it is desired to change delivery of material from one side of the vehicle to the other the bolts 170 of the chute are removed, and the chute fixed in position on the opposite side of the vehicle as indicated in dot dash line in Fig. 2. The direction of travel of the conveyor belt is changed by moving lever 143 in the direction opposite to that in which it is set thus engaging the previously disengaged gear of the pair of gears 148, 149 with gear 150.

It will be noted that the resilient bearing arrangement for the shaft 82 of the digging and shovelling means enables such means to adapt 30 itself to small differences in the surface of the road or street, and to absorb shocks, such as might be caused by an arm 95 striking a large stone, without breaking. However, should one of the arms be broken from any cause, or a plate 100 35 be cracked, the damaged part may be readily removed and replaced.

Although I have herein shown and described only one form of vehicular apparatus for removing snow and ice from roads, streets or highways, 40 it is to be understood that various changes and modifications may be made herein without departing from the spirit of my invention and the spirit and scope of the appended claim.

What I claim is:

45 In an apparatus for removing snow and ice from roads, streets and like surfaces, comprising a vehicle having a horizontal bed frame and an upright frame extending upwardly at one end thereof, said horizontal bed frame having front 50 and rear supporting wheels, the front wheels being spaced apart and located adjacent one end of the bed frame and on each side thereof, a single elevator conveyor including a pivotally inclined frame for supporting the same, the elevator conveyor and its supporting frame being of substantially the same width as the horizontal bed frame and extending lengthwise thereof, the elevator frame being pivoted adjacent the top of the upright frame and inclined downwardly at an 55 angle of approximately 45° with the upright frame, a mechanism carried by the bed frame and connected to the lower end of the elevator frame for raising and lowering the lower end of the elevator frame relative to the road or street surfaces over which the vehicle is passing, a horizontal conveyor extending along the top of the upright frame and cross-wise in relation to the horizontal bed frame, the horizontal conveyor being mounted directly above the front supporting 60 wheels, one edge of the horizontal conveyor being slightly beneath the upper end of the inclined conveyor to receive the snow and ice carried up the inclined conveyor, an elongated horizontal rotor mounted upon a horizontal shaft; the 65 rotor being of substantially the same width as

70 75

the inclined elevator conveyor and having means for mounting the same under the lower end of the supporting frame of the inclined conveyor for detaching the snow and ice from the road surface, said rotary supporting means consisting of a pair of arms extending forwardly and substantially horizontally from and under the lower end of the inclined conveyor frame and in a plane substantially parallel with the side of the said frame and a corresponding vertical supporting bracket extending downwardly from each side of the said frame to the outer end of the horizontal arms and fixedly connected thereto, the junction of the arms and brackets having vertical guideways formed therein, a bearing block carried within each guideway for supporting the shaft, a resilient member carried between the tops of the guideways and the bearing blocks for resiliently supporting the said blocks to provide for a limited upward movement of the rotor should the rotor come in contact with an obstruction, the said rotor having a plurality of radial blades of equal length secured to the horizontal shaft, a curved scooping blade secured to and under the lower end of the inclined elevator frame and located immediately in rear of the rotor, the lower edge of said blade being substantially in a horizontal plane with the lowest point of the rotating blades of the rotor, the scoop extending upwardly and around the lower end of the elevator conveyor and terminating above the upper surface thereof

5
10
15

for receiving the snow and ice from the rotor end depositing the same on the upper surface of the inclined conveyor, a rolling support carried on the lower end of the inclined conveyor for guiding the lower end of the scoop and rotor a predetermined distance from the road surface, a single power plant carried rearwardly of the lower end of the inclined conveyor for operating the rotor, the inclined and horizontal conveyors and for moving the vehicle along and over the road or street surfaces.

8
